UNITED STATES PATENT OFFICE.

HERMAN H. BRANDES, OF CORYDON, KENTUCKY.

BRIDLE-BLIND.

No. 921,072.

Specification of Letters Patent.

Patented May 11, 1909.

Application filed June 16, 1908. Serial No. 438,854.

To all whom it may concern:

Be it known that I, HERMAN H. BRANDES, a citizen of the United States, residing at Corydon, in the county of Henderson and 5 State of Kentucky, have invented a new and useful Bridle-Blind, of which the following is a specification.

The invention relates to improvements in bridle blinds.

10 The object of the present invention is to improve the construction of bridle blinds, and to provide a simple and inexpensive blind, adapted to be readily applied to any ordinary bridle without employing winker 15 straps or braces, so that there will be no liability of winker straps, braces, or other straps connected with the bridle blinds of becoming hooked or caught on a post, or other object, and the blinds thereby injured, 20 while a horse is rubbing its head against such post or other object.

Another object of the invention is to provide a pair of laterally extending bridle blinds, adapted to obscure the view at the 25 back and afford an unobstructed view at the front and sides, and at the same time render the bridle cooler than those equipped with the ordinary blinds.

With these and other objects in view, the 30 invention consists in the construction and novel combination of parts hereinafter fully described, illustrated in the accompanying drawing, and pointed out in the claims hereto appended; it being understood that 35 various changes in the form, proportion, size and minor details of construction, within the scope of the claims, may be resorted to without departing from the spirit or sacrificing any of the advantages of the invention.

40 In the drawing:—Figure 1 is a perspective view of a bridle applied to a horse's head and provided with blinds, constructed in accordance with this invention. Fig. 2 is 45 a longitudinal sectional view of one side of the bridle. Fig. 3 is a transverse sectional view, taken on the line 3—3 of Fig. 2. Fig. 4 is a detail perspective view of one of the blinds equipped with a box loop and side 50 strap. Fig. 5 is a similar view, the box loop and side strap being removed.

Like numerals of reference designate corresponding parts in all the figures of the drawing.

55 Each blind 1 extends laterally from opposite sides of a bridle 2, and consists of an

upper substantially lobe-shaped portion 3, and a lower downwardly tapered portion 4. The upper lobe-shaped portion is located in rear of the eye of the animal, and it extends 60 slightly above the same, as clearly illustrated in Fig. 1 of the drawing, so that the blinds are adapted to cut off the view from the rear and afford an unobstructed view at the front and sides, and they leave 65 the front of the bridle entirely open and thereby render the bridle much cooler than bridles equipped with forwardly extending blinds. The blind 1 is composed of two 70 layers or plies 5 and 6 of leather, or other suitable material, secured together at the outer curved edges by a row of stitching 7, or other suitable means, and the inner longitudinal edges of the plies or thicknesses are bent at right angles to form an attaching 75 flange 8. The straight longitudinal edges of the plies at the attaching flange 8 are arranged in flush relation, and it will be apparent, from Fig. 3 of the drawing, that the layer or ply 6, which is bent around the layer 80 or ply 5, requires slightly more material than the latter, so that when the layers or plies of the attaching flange are secured together, the material of the layer or ply 6 will operate to retain the blind and the attaching flange in their angular relation, and will resist any tendency of the blind to 85 change its position. The plies or layers of the attaching flange 8 are secured together by spaced attaching means 9, which also 90 serve to secure a box loop 10 and a side strap 11 to the attaching flange. The upper attaching means may consist of spaced rows of stitching, tacks, or any other suitable means. The blinds are solely supported by 95 the side straps, being attached to the same at their inner longitudinal edges only, and their upper and outer edges are entirely free and are not connected to or braced by winker straps, so that when a horse rubs its 100 head against a post, or other object, there will be no winker straps or braces to become caught on such post, and the liability of the blinds to injury from such cause will be entirely eliminated.

105 The box loop 10, which is of the ordinary construction, extends longitudinally of the attaching flange and is arranged in the angle formed by the same and the blinds, as clearly illustrated in Fig. 3 of the drawing. 110 The box loop by being arranged at the rear face of the blind in the angle formed by the

same and the attaching flange is adapted to prevent the blind from flapping and thereby annoying the animal. By being arranged in the angle formed by the attaching flange 5 and the blind 1, the box loop supports the blind to prevent the same from flapping backwardly, and it stiffens the blind to prevent the same from flapping forwardly. The side or cheek strap 11 is doubled to 10 form two sides 12 and 13, which provide a loop 14 at the top of the flange 8 for an upper buckle 15. The front side portion 12 of the side strap extends through the box loop and has a lower tapered terminal 16, 15 arranged below the lower end of the blind and secured by stitches 17, or other suitable means to the other side portion 13, as clearly shown in Fig. 2 of the drawing. The side portion 13, which is arranged exteriorly of 20 the box loop, extends downward from the top of the attaching flange at the inner or rear face of the same, and it is doubled on itself below the attached ends 17 to form a lower loop 18 for the reception of the bit 25 ring 19. The free end 20 of the side strap engages a buckle 21, arranged at the lower end of the box loop and connected with the same by the attached end 17 and the rear side 13. The attached end portion 17 is 30 provided with a slot 22 for the passage of the tongue of the buckle 21, and the inner transverse bar of the frame of the buckle is arranged between the end 17 and the rear side 13. The tongue of the upper buckle 35 passes through a slot 23 of the loop 14, and it is adapted to engage the adjacent end of the head stall 24 of the bridle. The free end of the side strap engages the lower buckle and extends into the lower end of the box 40 loop. The blind by being equipped with the box loop and the side strap constitutes a bridle attachment, and may be readily applied to any ordinary bridle.

The blinds, which extend laterally from 45 the opposite sides of the head of an animal, do not close the bridle either at the sides or at the front, so that a bridle equipped with the blinds 1 is as cool as an ordinary open bridle without blinds. The bridle blinds, 50 which are comparatively small, may be cheaply manufactured as only a comparatively small amount of material is employed in the construction of the blinds.

Having thus fully described my invention, 55 what I claim as new and desire to secure by Letters Patent, is:—

1. A bridle including a blind extending laterally throughout its length from the side or cheek strap and provided at its inner 60 edge with a narrow longitudinal attaching flange extending rearwardly from the blind at right angles thereto and secured to the side or cheek strap, and a box loop secured to the flange and extended in the angle 65 formed by the flange and the blind, and

abutting against and supporting the latter to prevent the blind from flapping backwardly and retaining the blind in position without the use of a winker brace.

2. A bridle including a blind extending laterally throughout its entire length from 70 the bridle and provided at its inner edge with a narrow longitudinal flange extending from the blind at right angles thereto, a box loop arranged in the angle formed by the flange and the blind, and abutting against and supporting the latter to prevent the blind from flapping backwardly and retaining the blind in position without the use of a winker brace, a side strap having 75 a doubled portion, one side of which is passed through the box loop and the other side being arranged exteriorly of the rear face of the attaching flange, and fastening means piercing the sides of the doubled portion of the strap and securing the box loop, 80 the flange and the strap together.

3. A bridle including a blind extending laterally throughout its entire length from the side of the bridle, and composed of two 90 layers or thicknesses united at the outer edge of the blind and bent at right angles at their inner longitudinal edges to form an attaching flange, the plies or thicknesses of the attaching flange being secured together, 95 after they are bent, to maintain the flange and the blind in their angular relation.

4. A bridle including a blind extending laterally throughout its entire length from the side of the bridle and provided at its inner edge with a narrow longitudinal attaching flange held at right angles to the blind, a box loop fitted in the angle formed by the blind, and abutting against and supporting the latter to prevent the blind from flapping backwardly and retaining the blind in position without the use of a winker brace, a side strap doubled to form two side portions, one of the side portions of the 100 strap being extended through the box loop and the other side portion being fitted 110 against the exterior of the attaching flange, fastening means for securing the strap, the box loop and the flange together, and buckles arranged at the ends of the box loop, one 115 end of the strap coöperating with the lower buckle and extending into the box loop.

5. A bridle including a blind extending laterally throughout its entire length from the side of the bridle and provided at its 120 inner edge with a narrow longitudinal attaching flange held at right angles to the blind, a box loop fitted in the angle formed by the attaching flange and the blind, and abutting against and supporting the latter 125 to prevent the blind from flapping rearwardly and retaining the blind in position without the use of a winker brace, a side strap doubled to form two side portions, one of the side portions of the strap being 130

extended through the box loop and the other side portion being fitted against the exterior of the attaching flange, fastening means for securing the strap, the box loop and the flange together, said strap having a free portion doubled to form a loop at the bottom of the blind and extending into the box loop, a lower buckle secured between the side portions of the side strap and coöperating with the free end of the strap, and

an upper buckle secured to the blind by the side strap and located at the upper end of the box loop.

In testimony, that I claim the foregoing as my own, I have hereto affixed my signature in the presence of two witnesses.

HERMAN H. BRANDES.
